UNITED STATES PATENT OFFICE.

EDGAR E. GREVE, OF BELLEVUE, PENNSYLVANIA.

ROPE CLAMP.

1,420,034.

Specification of Letters Patent. Patented June 20, 1922.

Application filed February 26, 1920. Serial No. 361,395.

To all whom it may concern:

Be it known that I, EDGAR E. GREVE, a citizen of the United States, residing at Bellevue, in the county of Allegheny and State of Pennsylvania, have invented certain new and useful Improvements in Rope Clamps, of which the following is a specification.

My invention relates to improvements in clamps for well drilling cables, and more particularly to what are commercially known as wire-rope clamps.

Wire-rope clamps of the class to which my invention relates have usually included a body portion having a centrally disposed opening extending through the body, a pair of opposed jaws operable by an eccentric action to clamp the cable, and having elongated body portions disposed within the opening, said elongated body portions being in contact throughout their lengths with the walls of the opening of the body. This construction is objectionable on account of the weight of the structure and the friction encountered in manipulating the parts, the friction being produced by the large area of contacting surfaces. Further objections to these clamps are the high cost of manufacture and the inability to readily change those parts most subject to wear and breakage.

Among the objects of the present invention are, to provide a clamp of the character specified of simple and efficient construction in which the friction is greatly reduced or entirely eliminated; a clamp in which the clamping action is effected by revolving the jaw members about fixed parallel axes of revolution and causing the clamping means to approach and recede from each other without a sliding motion, the movement of said clamping means being on an arc of a circle having its center the axis of the respective jaw members; a clamp capable of being manufactured at considerably less cost than heretofore; and a construction of such a character as to permit the ready removal and replacement of the parts subjected to wear and breakage during the use of the clamp.

In the accompanying drawings which illustrate an application of my invention,—

Fig. 1 is a top plan of a clamp embodying my invention;

Fig. 2, a front elevational view;

Fig. 3, a vertical sectional view taken on line III—III of Fig. 1;

Fig. 4, a sectional view taken on line IV—IV of Fig. 2; and

Fig. 5, a top plan showing the jaws spaced apart.

Referring to the drawings, 2 and 3 respectively designate spaced apart upper and lower curved and apertured plate or block members, and 4 vertically extending means, or, as illustrated, a headed bolt for connecting the two body members. The parts mentioned constitute a skeleton clamp body adapted to receive two opposing jaw-members. As illustrated, plates 2 and 3 are of similar construction, and each is formed with an opening 5 through which the connecting bolt 4 is passed, openings 6, and an open space or recessed portion 7. Bolt 4 at its upper end is provided with a head 8 while its lower end is threaded for the purpose of receiving a threaded lock-nut 9.

Disposed between the plates 2 and 3 is a pair of revoluble opposing jaw-members 10. Each jaw-member 10 is formed with an elongated body portion 11 extending from the upper to the lower plate of the clamp body, a pin or projecting member 12 at the upper end of the body portion adapted to be entered in one of the openings 6 in plate 2, and a similar pin at its lower end adapted to be entered in a corresponding opening 6 of the plate or block 3. A curved liner receiving extension 13 is also formed on the upper and lower ends of the body portion of each jaw-member. Extension 13 coming into contact with the top and bottom plates act as a stop to limit the opening of the jaws and to thereby prevent the cable engaging liners from being moved transversely out of register by preventing any substantial longitudinal movement of the jaws relatively to each other. From the above it will be noted that the axis of revolution of the respective jaw-members passes through the center of the pin or member 12 and that the axes of the jaw-members are parallel.

It will also be noted that the jaw-members are rotatably supported by and between the plates 2 and 3 of the skeleton clamp body and that the contacting surfaces, tending to produce friction between the clamp body and the jaws, are of a very small area

compared with clamps of this character as heretofore made.

In addition to the elements mentioned, each jaw member is provided with a projecting element 14 designed to receive the usual means, not shown, for suspending the clamp structure in a manner well known to those skilled in the art. 15 designates a retaining pin or bolt extending from the 10 downwardly depending portion of element 14 to the body portion of the jaw.

16 designates a laterally projecting arm from one jaw-member and 17 a similarly extending arm from the other jaw-member. 15 Arm 16 at its outer end is provided with an element receiving slot 18, and adjacent thereto and on the outer face of the arm, a notch 19 is formed.

Arm 17 is designed to carry the clamp 20 adjusting and locking means and for this purpose, said arm is enlarged at its outer end as indicated at 20, and is formed with a block-receiving recess 21, and with an opening through which the clamp adjusting member 22 is passed. Member 22 is pivotally mounted in arm 17, this mounting, as shown, being effected by the employment of a block member 23 through which threaded member 22 extends.

30 Block 23 is provided with extensions 24, and 25 designates bolts entered in openings of lugs 25', these bolts being employed for maintaining the block within the recess. Block 23 is threaded to cooperate with the 35 threads 26 of member 22. Member 22 at one end is provided with an operating handle 27 and mounted on said member at or near its opposite end is a casting or integral structure including a body portion 28, a 40 handle 29, and an elongated lug 30, the latter being adapted to enter the notch or recess 19 of arm 16. 31 designates a lock-nut mounted on the threaded member 22 beyond the body portion 28 above referred to.

45 Extending throughout the length of the body portions of the jaws and projecting above and below the ends thereof, are liners 32. For the purpose of receiving said liners, each jaw-member has a semi-circular 50 elongated recess 33 and a centrally disposed recess or depression 34, the latter being designed to receive an enlarged portion 35 of the liner 32. By means of the depression 34 in which part 35 is entered and the 55 countersunk bolts 36 passed through the extensions 13 of the body portion of the jaws, the liners are securely held in position for gripping the rope or cable C. It will be understood that liners differing in sizes 60 may be employed in this construction in order to adapt the clamp for use with rope or cables of various diameters, and that the construction is such as to enable the removal and replacement of the liners with 65 very little trouble.

In the use of the clamp, the clamp is placed on the cable by first separating the arms of the movable jaw members, thus permitting the cable to be passed into position to be gripped by the liners. The arms are 70 then moved towards each other and the adjusting member 22 swung around on its pivot point until a portion thereof enters slot 18 of arm 16 and the lug 30 engages the notch 19. Operating handle 27 is then 75 turned, thereby actuating the adjusting screw member 22 for the purpose of drawing the arms together and causing the cable to be effectively gripped. The clamp is released from the cable by reversing the 80 operation of the parts just described.

In manipulating the clamp, either to close or open the same, the jaws together with the rope or liner receiving recesses approach and recede from each other without a sliding motion and the recesses and the liners disposed therein are caused to move on arcs of circles having their centers the fixed axes of rotation of the said jaw members.

What I claim is:

1. In a rope clamp, a skeleton body including vertically spaced apart apertured members and means connecting said members, opposing jaw members positioned between the body members each including an elongated body portion, longitudinally extending means carried by said jaws and projecting into the body members providing pivots for the jaws, arms carried by the jaws, and cooperating jaw adjusting means 95 carried by the arms.

2. In a rope clamp, a skeleton body including an upper and a lower spaced apart apertured member, separable means connecting said members, opposing jaw members positioned between the upper and lower body members each including an elongated body portion provided with an extension at each end entered in openings of the body members, an arm on each jaw member, and cooperating jaw-adjusting means carried by the arms.

3. In a rope clamp, a skeleton body including two spaced apart apertured members, vertically extending means connecting said members, a jaw member having an elongated body portion disposed between the said body members, a member extending from the upper end of the jaw body portion and entered in an opening of a body member, and a member extending from the lower end of the jaw body portions and entered in an opening of the other body member.

4. In a rope clamp, a skeleton body including two spaced apart apertured members, vertically extending means connecting said members, a jaw member having an elongated body portion disposed between the said body members, a member extending from the upper end of the jaw body por- 125

tion and entered in an opening of a body member, a member extending from the lower end of the jaw body portion and entered in an opening of the other body member, said 5 jaw member having at one end of its body portion a liner receiving extension.

5. In a rope clamp, a skeleton body including two spaced apart apertured members, vertically extending means connecting 10 said members, a jaw member having an elongated body portion disposed between the said body members, a member extending from the upper end of the jaw body portion and entered in an opening of a body mem- 15 ber, a member extending from the lower end of the jaw body portion and entered in an opening of the other body member, said jaw member having at one end of its body portion a liner receiving extension and 20 means for securing a liner to said extension.

6. In a rope clamp, a body, a pair of opposed revoluble jaw members having spaced apart fixed axes of revolution arranged in parallelism, said axes being formed by co- 25 acting means on the jaws and body, each jaw member being formed with a rope receiving recess disposed therein and movable in an arc of a circle having as its center the axis of rotation of the jaw member, and means 30 on the jaw members for contacting with the body for preventing the rope receiving recesses of the jaws from being moved transversely any substantial distance out of regis- tering position with each other.

35 7. A rope clamp comprising a supporting

frame, a pair of jaws pivotally supported in the frame, each of the jaws having a separate axis of rotation, and movable independently of each other the two axes being parallel, rope engaging means on each jaw 40 and arranged to swing in an arc of a circle the center of rotation of which is the axis of rotation of the jaw, and an extension on the jaws for engagement with the frames for preventing the jaws from moving longitudinally relatively to each other. 45

8. A rope clamp comprising a supporting frame, a pair of jaws pivotally supported in the frame, each of the jaws having a separate axis of rotation, and movable inde- 50 pendently of each other which axes are parallel with each other, relatively small spaced apart rope clamping portions at each end of the jaws, said rope clamping portions on each jaw being spaced from each 55 other and so positioned that they swing in an arc of a circle whose center is the center of rotation of their respective jaws, and means for holding the jaws in clamping relation, and an extension on the jaws for 60 engagement with the frames for preventing the jaws from moving longitudinally relatively to each other.

In testimony whereof I affix my signature in presence of two witnesses.
